COAL HANDLING SYSTEM

Paul L. Betz, Baltimore, Md., and Sebastian Karrer, Washington, D. C., assignors to Consolidated Gas Electric Light and Power Company of Baltimore, Baltimore, Md., a corporation of Maryland

Application February 6, 1946, Serial No. 645,864

6 Claims. (Cl. 214—17)

1

This invention relates to systems for handling coal in power plants, and more particularly to such systems wherein the coal is supplied to pulverizers or stokers from elevated storage spaces.

In modern power plants, the uninterrupted delivery of coal from the storage bunkers to the pulverizing mills or stokers is of great importance. In practice, however, coal stoppages frequently result, usually from excessive moisture in the coal, and on occasion are of such a nature as to result in a lowering of the output of the steam boilers. The present invention is intended to minimize such stoppages.

In many central station power plants, the coal leaves the storage bunker by gravity and passes into steel chutes of large cross sectional area which convey the coal to the pulverizing mill or stoker located at a lower level than the bunker. These chutes are normally of considerable length since they must extend from the bunker, located near the roof of the power plant, to the operating floor for the boiler, near the ground level. When the moisture content of the coal is low, little difficulty is experienced with such a system. With increased moisture content, however, common during the winter months and especially when lot-stored coal is used, coal flow is maintained with considerable difficulty, it often being necessary to resort to manual methods for overcoming the sticking of coal both in the bunker and in the chutes.

In the usual gravity feed system heretofore known, the chutes deliver the coal to a feeding device located immediately adjacent the pulverizing mill.

In such an arrangement, the entire chute system between the bunker and the feeder is normally completely filled with coal, and the only regulation of the flow of coal through the system is by control of operation of the feeder. Consequently, the velocity of coal movement is relatively small, the cross sectional area of the chutes is relatively large in order to insure the passage of coal, and the total quantity of coal in transit is, therefore, large. For example, in a typical central station power plant of the character described, the coal velocity is on the order of 0.02 foot per second, the cross sectional area of the chute is about 6 to 7 square feet, and the total quantity of coal in transit at any instant is approximately 8 tons.

It is one of the objects of the present invention to provide a new and improved system for handling coal in power plants wherein the chutes are normally only partially filled with coal moving at

2

a high velocity, and wherein the coal is fed to the chutes at approximately the same rate as it is delivered to the pulverizing mill or stoker.

Another object is to provide a novel coal handling system of the character described wherein the quantity of coal moving through the chutes at any instant is extremely small in comparison with prior systems, and thereby enables the use of substantially lighter, more flexible chute construction.

A further object is to provide an improved coal handling system wherein the delivery of coal from the bunker into the chutes is automatically controlled so as to prevent flooding or choking of the system, and which is so designed that, when operation of the system is discontinued, the chutes are normally empty of coal.

These and other objects will appear more fully upon consideration of the detailed description of 20 certain embodiments of the invention which follows. In this connection, although three specifically different forms of coal handling system are described and illustrated in the accompanying drawing, it is to be expressly understood that this 25 drawing is for purposes of illustration only and is not to be construed as defining the scope of the invention, for which latter purpose reference should be had to the appended claims.

Referring now to the drawing, wherein like 30 reference characters indicate like parts throughout the several views:

Fig. 1 is a schematic elevational view of one form of coal handling system embodying the present invention; and

Figs. 2 and 3 are similar views representing modifications of the system shown in Fig. 1.

In the coal delivery system illustrated in Fig. 1, the reference numeral 11 indicates a portion of an elevated storage bunker which is adapted to supply coal to a pulverizing mill 12, the latter being provided with fuel feeding outlets or tubes 13 through which pulverized coal and air pass on their way to the boiler burners (not shown). The bunker 11 has a pair of outlets 14 each of which is adapted to convey coal to a feeding device 15 which is driven in any suitable controllable manner, as by an electric motor 16. The feeders 15 may be of any of the well-known screw, reciprocating, belt, star or rotary disc types, and may be of the construction illustrated in copending application Serial No. 698,964, now Patent No. 2,529,445, dated November 7, 1950, which provides a pressure seal between the atmosphere and the chute system next to be described.

The feeders 15 supply coal to the upper ends of

a pair of subsidiary chutes 17 which connect at their lower ends with a main chute 18, the latter in turn having its outlet end connected to the top of a hopper 19 located closely adjacent the pulverizing mill 12. The bottom of hopper 19 feeds directly into another feeding device 20 which is controllably driven in the same manner as chute feeders 15, as by an electric motor 21, and delivers coal to the mill 12 in known manner. The mill feeder 20 may be of any desired construction, and is usually a component part of the pulverizing mill, the structural details of which form no part of the present invention.

The drive motors 16 and 21 of chute feeders 15 and mill feeder 20 are provided with suitable electrical supply circuits 22 and 23, respectively, which are connected to the main supply line 24 through a switch 25. Although the normal feeding rate of feeders 15 combined is so designed as to be approximately equal to that of feeder 20, means are provided for insuring a continuous supply of coal to the mill feeder 20 in spite of minor variations in feeding rate that may occur in the operation of the chute feeders 15. To this end, the storage capacity of hopper 19 is substantially greater than that necessary to accommodate the amount of coal normally in transit through the system, and provides a reserve of coal ready for delivery to mill feeder 20 sufficient to compensate for brief periods of decreased flow of coal through the chutes 17 and 18, such as may be caused by slowing down of feeders 15 or failure of the coal to discharge properly from the bunker 11.

Hopper 19 is also provided with automatic control means for stopping, or reducing the speed of, the motors 16 which drive the chute feeders 15 in the event that coal is supplied to the hopper faster than it is delivered therefrom to the pulverizer 12 by feeder 20, and the level of the coal in the hopper rises above a predetermined point. As shown diagrammatically in the embodiment illustrated, hopper 19 is provided with a coal-level responsive switch means 26 which is connected by leads 27 to a relay 28, the latter being interposed between the supply lines 22 for the motors 16 and the switch 25 in the main supply line 24. Any suitable level responsive switch may be used at 26. Several such switches are available commercially, one employing a tubular mercury switch that responds to the pressure of the coal against a relatively movable portion of the side wall of the hopper. A suitable level responsive switch is also shown in Hayes Patent No. 2,429,159, granted October 14, 1947. In the event that the level of the coal in hopper 19 rises sufficiently to actuate switch 26, the relay 28 operates to either stop the motors 16, or reduce their speed, until the flooded condition of the hopper is corrected by the continued operation of mill feeder 20. Where motors 16 are stopped upon actuation of level responsive switch 26, relay 28 may consist of the usual contact making and breaking device that disconnects motor leads 22 from the main supply line 24. Where alternating current is employed and the speed of motors 16 is to be reduced upon actuation of level responsive switch 26, relay 28 would transfer the circuit connections of the motor so as to increase the number of poles in the motor, and where direct current is used, relay 28 would operate to decrease the voltage applied to the armature as by inserting a resistance in series with the armature circuit or to increase the field current as by shunt-

ing a resistance in the field circuit. The location of switch means 26 in hopper 19 is preferably such that the storage space in the hopper above the switch is at least equal in volume to the volume of coal normally contained in the subsidiary and main chute members 17 and 18, so that when the entire system is shut down by opening main switch 25, space will be available for receiving all of the coal then in transit in the chute system.

In order to assist in effecting a uniform flow of coal from bunker 11 through outlets 14 and into chute feeders 15, the bunker may be equipped with suitable means, indicated at 29, for positively assisting in emptying the bunker. For example, the bunker emptying means 29 may comprise devices for vibrating the walls of the bunker, several forms of which are available commercially. One commercial device suitable for this purpose employs an electromagnet that is operated on alternating current. Another device employs a motor with a relatively large unbalanced weight that produces the desired vibration. A suitable device for this purpose is also disclosed in Francis Patent No. 2,276,382, granted March 17, 1945. The bunker emptying means 29 may be operated either continuously during operation of the entire system, or intermittently as dictated by the coal flow conditions existing in the chute feeders 15 or chutes 17 and 18. In the latter case, proper operation may be insured by installing electrical contacting devices (not shown) in feeders 15 or chutes 17 and 18 which are responsive to the movement of coal for controlling energization of bunker emptying means 29.

The modified system shown in Fig. 2 differs primarily from the embodiment of Fig. 1 in that only a single chute feeder is employed to control the flow of coal from two bunker outlets. As shown, the bunker outlets 14 discharge into a pair of subsidiary chutes 30 the lower ends of which are connected to the inlet of a chute feeder 31, the latter being driven in any suitable manner, as by an electric motor 32. The supply circuit 33 of motor 32 is connected to the main supply line 24 through a relay 28, which is in turn actuated by a coal-level responsive switch 26, just as in the system of Fig. 1.

Where desirable, another coal-level switch (not shown in the drawing) may be installed in hopper 19 at a lower level than switch 26 to set the lower limit to which the coal level may fall. Actuation of this switch due to low coal level causes relay 28 to increase the rate of feed of chute feeders 15 in Fig. 1 and chute feeder 31 in Fig. 2, thereby building up the quantity of coal stored in hopper 19. Where the speed of the feeder motors is to be increased on operation of the low level responsive switch relay means would be provided in the circuit of motors 16 or 32 to decrease the number of poles where alternating current is used. Where direct current is used, the motor speed may be increased by increasing the armature current as by short-circuiting a resistance in the armature circuit, or by decreasing the field current as by increasing the resistance of the field circuit. The coal in hopper 19 also serves as a pressure sealing column where non-pressure sealing chute feeders are employed.

The chute feeder 31 is normally driven by the motor 32 at a speed such as to deliver coal to the main chute 18 at a rate approximately equal to that at which the mill feeder 20 withdraws 75 coal from the hopper 19. Since in this embodi-

ment of the invention the subsidiary chutes 38 are normally solidly filled with coal, said chutes may be provided, if desired, with vibrators or other suitable means 34 which, together with bunker emptying means 29, insure a steady flow of coal to chute feeder 31. As in the case of bunker emptying means 29, chute emptying means 34 may be operated either intermittently, whenever the flow of coal feeder 31 is interrupted, or continuously during the operation of said feeder.

In the embodiments of the invention illustrated in Figs. 1 and 2, both chute feeders and mill feeders are employed, the former controlling the rate of feed of coal into the chute system, and the latter controlling the rate of discharge of coal from the storage hopper associated with the outlet of the main chute. The arrangement shown in Fig. 3 employs chute feeders only, and omits the storage hopper and mill feeder of the other two forms of the invention. As shown in Fig. 3, the chute feeders 35 regulate the flow of coal into subsidiary chutes 17 which in turn feed the main chute 18, just as in the case of Fig. 1. Chute feeders 35 are of the pressure sealing type and are preferably of the construction illustrated in the aforesaid Patent No. 2,529,445, and may be driven in any suitable manner, as by electric motors 36. The use of pressure sealing chute feeders 35 is necessary as otherwise the proper pressure could not be maintained within chutes 17 and 18 and in pulverizing mill 12. The main chute 18 delivers coal directly into pulverizing mill 12, the rate of coal flow being controlled solely by the feeding rate of the feeders 35. Since only a relatively small amount of coal is involved, the mill 12 would normally provide sufficient storage capacity to accommodate all of the coal in transit in the chute system when operation of feeders 35 is discontinued. If desired, however, a small hopper (not shown) may be installed between the outlet of chute 18 and pulverizing mill 12 in order to provide additional storage capacity.

There is thus provided by the present invention a coal handling system wherein, when the system is not in operation, the chutes are normally empty of coal. In order to put the system into operation, the switch 25 in the main supply line is closed so as to start the mill and/or chute feeders; and since coal is fed to an initially empty chute at approximately the same rate that it leaves the chute, no accumulation of coal takes place in the chute and the chute runs only partially filled even when operating at full load. By positioning the chute feeders adjacent the storage bunker and inclining the chutes at suitable angles approaching the vertical, high velocity coal flow through only partially filled chutes is obtained, in direct contrast with the older systems wherein the only feeders employed are adjacent the pulverizing mill and the chute system is completely filled with coal moving at an extremely low velocity. For example, in systems employing the present invention, the average coal velocity is measured in feet, rather than hundredths of a foot, per second, and the total quantity of coal in the chute system at any instant may be as little as 10 pounds, as compared with 8 tons in the older types of system.

Figs. 1, 2 and 3 indicate the application of the present invention to new chute construction. The invention is equally applicable, however, to existing chute installations which, while of enormously excessive capacity as far as the

requirements of the present invention are concerned, will nevertheless perform satisfactorily when adapted for use in accordance with the foregoing disclosures.

Another advantage of the present invention resides in the fact that, whereas the chutes of prior systems are of massive construction requiring welded or riveted steel plate wall members to support the tons of coal which solidly fill the chutes, the chutes employed in systems embodying the present invention contain only a few pounds of coal and need not be of large cross-sectional area. The chutes may be constructed of steel pipes or of relatively flexible tubular members. The use of small diameter pipes for chutes is of advantage in that it permits the ready substitution of an empty chute for one which may have become obstructed due to the lodging of foreign bodies therein, and also increases the ease with which structural members in the power plant may be avoided when positioning the chutes.

While three specifically different coal handling systems embodying the invention have been described and illustrated in the accompanying drawing, it will be obvious that the invention is not limited to the particular arrangements shown, but is capable of a variety of mechanical embodiments. For example, while the invention has been described in association with bunker means having two outlets per pulverizing mill, it is to be understood that it is equally applicable to any other form of coal storage means, such as bins, silos and the like, having one outlet per pulverizing mill. It will also be recognized that, although examples have been given of specific types of feeders, vibrators and other elements suitable for use in the system of the present invention, the specific construction of these devices is not essential to the inventive concept and that various equivalent means are acceptable in the overall combination.

Various other changes which will now suggest themselves to those skilled in the art may be made in the form, details of construction and arrangement of the parts without departing from the inventive concept. Reference is therefore to be had to the appended claims for a definition of the limits of the invention.

What is claimed is:

1. In a coal handling system for power plants adapted to deliver coal continuously to a coal receiving device such as a pulverizing mill, the combination therewith of an elevated coal storage means relatively remote from said device, a storage hopper adjacent said device, a chute adapted to receive coal from said storage means and deliver it to said storage hopper, the lower end of said chute being open and unobstructed and delivering coal directly into said hopper, said hopper having an outlet at its lower end connected to said device through which coal is discharged from the hopper by gravity, whereby the coal in said hopper is adapted to serve as a seal between the air pressures existing in said device and in the space above the level of the coal in said hopper, means for feeding coal from said storage means to the upper end of said chute, and motor means for driving said feeding means at different rates of feed, said storage hopper having a volume at least sufficient to accommodate all of the coal in transit in said chute at the maximum feeding rate of said feeding means in addition to the coal in said hopper when operation of said motor means is discontinued.

2. In a coal handling system for power plants adapted to deliver coal continuously to a coal receiving device such as a pulverizing mill, the combination therewith of an elevated coal storage means relatively remote from said device, a storage hopper adjacent said device, a steeply inclined chute adapted to receive coal from said storage means and deliver it to said storage hopper, the lower end of said chute being open and unobstructed and delivering coal directly into said hopper, said hopper having an outlet at its lower end connected to said device through which coal is discharged from the hopper by gravity, whereby the coal in said hopper is adapted to serve as a seal between the air pressures existing in said device and in the space above the level of the coal in said hopper, means for feeding coal from said storage means to the upper end of said chute, motor means for driving said feeding means at different rates of feed, and means for so controlling said motor means that coal is fed into said chute at approximately the same rate as that at which it is delivered thereby into said hopper, whereby the chute is normally only partially filled with coal when the system is in operation, said storage hopper having a volume at least sufficient to accommodate all of the coal in transit in said chute at the maximum feeding rate of said feeding means in addition to the coal in said hopper when operation of said motor means is discontinued.

3. In a coal handling system for power plants adapted to deliver coal continuously to a coal receiving device such as a pulverizing mill, the combination therewith of an elevated coal storage means relatively remote from said device, a storage hopper adjacent said device, a chute adapted to receive coal from said storage means and deliver it to said storage hopper, the lower end of said chute being open and unobstructed and delivering coal directly into said hopper, said hopper having an outlet at its lower end connected to said device through which coal is discharged from the hopper by gravity, whereby the coal in said hopper is adapted to serve as a seal between the air pressures existing in said device and in the space above the level of the coal in said hopper, motor driven means for feeding coal from said storage means to the upper end of said chute, continuously operable motor driven means for feeding coal from the outlet of said hopper to said device, and means responsive to the amount of coal in said hopper for so controlling the relative speeds of operation of said motor driven feeding means that coal is fed from said storage means to said chute at approximately the same rate as that at which it is fed from said hopper to said device, said hopper having a volume at least sufficient to accommodate all of the coal in transit in said chute at the maximum feeding rate of said first named feeding means in addition to the coal in said hopper when operation of said means is discontinued.

4. A coal handling system as defined in claim 3 wherein the chute is steeply inclined and of such diameter in relation to the feeding rate of said first named feeding means that the chute is normally only partially filled with coal when the system is in operation.

5. In a coal handling system for power plants adapted to deliver coal continuously to a coal receiving device such as a pulverizing mill, the combination therewith of an elevated coal storage means relatively remote from said device, a storage hopper adjacent said device and having its

outlet connected to the latter for the delivery of coal thereto, a chute adapted to receive coal from said storage means and deliver it to said storage hopper, the lower end of said chute being open and unobstructed and delivering coal directly into said hopper, motor driven means for feeding coal from said storage means to the upper end of said chute, continuously operable motor driven means for feeding coal from the outlet of said hopper to said device, and relay means including a switch responsive to the level of the coal in said hopper for so controlling the speed of operation of said first named feeding means that coal is fed thereby from said storage means to said chute at approximately the same rate as that at which it is fed by said second named feeding means from said hopper to said device, the volume of said hopper above the level of said switch being at least sufficient to accommodate all of the coal in transit in said chute at the maximum feeding rate of said first named feeding means when operation of said means is discontinued.

6. In a coal handling system for power plants adapted to deliver coal continuously to a coal receiving device such as a pulverizing mill, the combination therewith of an elevated coal storage means relatively remote from said device, a storage hopper adjacent said device, a chute adapted to receive coal from said storage means and deliver it to said storage hopper, the lower end of said chute being open and unobstructed and delivering coal directly into said hopper, said hopper having an outlet at its lower end connected to said device through which coal is discharged from the hopper by gravity, whereby the coal in said hopper is adapted to serve as a seal between the air pressures existing in said device and in the space above the level of the coal in said hopper, motor driven means for feeding coal from said storage means to the upper end of said chute, continuously operable motor driven means for feeding coal from the outlet of said hopper to said device, and control means responsive to variations in the level of the coal in said hopper with reference to a predetermined level for so controlling the operation of said first named feeding means that coal is fed thereby from said storage means to said chute at approximately the same rate as that at which it is fed by said second named feeding means from said hopper to said device, the volume of said hopper above said predetermined level being at least sufficient to accommodate all of the coal in transit in said chute at the maximum feeding rate of said first named feeding means when operation of said means is discontinued.
